UNITED STATES PATENT OFFICE.

EBER J. HUBBARD, OF BERWYN, ILLINOIS.

SPOOL.

1,293,443.

Specification of Letters Patent.

Patented Feb. 4, 1919.

Application filed April 17, 1918. Serial No. 229,002.

To all whom it may concern:

Be it known that I, EBER J. HUBBARD, a citizen of the United States, and a resident of Berwyn, in the county of Cook and State 5 of Illinois, have invented certain new and useful Improvements in Spools, of which the following is a specification.

My invention relates to spools, particularly to sheet metal spools useful in cotton 10 and woolen mills for holding yarn.

The object of the invention is to produce a sheet metal spool which is light, strong and rigid, and whose ends are so constructed and arranged that the spool can operate 15 efficiently during unwinding of the yarn therefrom, and the spool can be readily inserted in a lathe or other winding machine to be refilled with yarn.

The various features of my invention are 20 fully disclosed on the accompanying drawing in which—

Figure 1 is a side elevational view with one end in vertical diametral section,

Fig. 2 is an end view, and

Fig. 3 is a sectional view of a cap member on plane 3—3, Fig. 2.

The core 5 of the spool is cylindrical and is formed by rolling up a rectangular piece of sheet metal whose edges have respectively 30 the dove-tail extensions 6 and the correspondingly shaped notches 7, the tongues fitting into the notches to hold the core edges intimately and securely together. At the ends of the core are the tongues 8 which extend through the slots 9 formed in the spool heads 10 and 11. After insertion of these tongues through these slots they are turned over outwardly and against the outer faces of the heads 10 and 11 and are preferably 35 spot welded to the heads. The heads are further connected together by the axially extending tube 12 whose ends 13 extend through the openings 14 in the heads and are turned radially outwardly and deflected 40 against the heads as clearly shown.

The outer peripheral sections of the heads are spun or otherwise turned outwardly and radially inwardly to form flanges 15 of substantially semi-circular cross-section, these 45 flanges greatly strengthening the heads. Secured against the outer faces of the heads are the cap frames 16 and 17. These caps are cylindrical and are secured by means of tongues 18 extending radially from the inner edges of the caps and spot welded to the outer faces of the heads. Each

cap has a central opening 19 in line with the tube 12, and between the central opening and the outer edge of the cap one or more slots 20 are provided. To fill in the space 60 between the head flanges 15 and the respective cap frame I preferably utilize a filler 21 of mill board, paper, wood, or some composition, this filler being applied before the flanges 15 are formed, the filler being then 65 intimately held in place by the flanges. The filler may be treated by soaking in moisture protective material, such as shellac.

A spool constructed as above is light yet 70 very strong and rigid, the formed up ends having the strength of solid heads. When a full spool is to be used it is slipped over a spindle extending from a support, the spindle being received through the opening 19 of one cap, and the tube 12 guiding the 75 spindle end accurately through the opening 19 of the opposite cap. If the spool supporting base is wider than the diameter of the spool ends then it will be engaged by the outer end of the metal flange 15. Ordinarily, however, friction contact is desired 80 in order that the unwinding of the yarn will be more or less braked or retarded. The supporting base for the spool is then of less diameter than the spool ends so that the 85 filler 21 only will engage with the base, and where a wood, paper, or composition filler engages with a metal supporting base, the friction will efficiently retard the spool during the unwinding operation. It will be 90 noted that the outer faces of the caps are slightly within the outer faces of the fillers so as not to interfere with the frictional engagement of the fillers with the supporting 95 bases.

The central openings 19 of the caps serve to receive the centering points of the lathe or other winding machine and the slots 20 receive the projections or pins on the lathe for turning the spool after centering thereof. 100

I do not desire to be limited to the exact construction and arrangement shown and described as changes and modifications are no doubt possible which would still come within the scope of the invention. 105

I claim as follows:

1. In a spool, the combination of a cylindrical core, sheet metal ends secured to said core and having their peripheral edges deflected outwardly and inwardly to form 110 rounded flanges, sheet metal caps secured to the outer faces of said ends and having cen-

tral openings for receiving spindles for receiving lathe centering points, and filler material between said caps and end flanges.

2. In a spool, the combination of a cylindrical core, sheet metal ends secured to the core and having their peripheral sections deflected outwardly and inwardly to form strengthening flanges, sheet metal caps secured against the outer faces of said ends 10 and having radially extending tongues spot welded to said ends, said caps having central openings for receiving spindles or lathe centering points and having off-center openings for receiving lathe turning projections, 15 and filler material filling the space between said caps and flanges, the outer faces of said caps being inwardly a distance from the outer faces of said filler material.

3. In a spool, the combination of a sheet 20 metal cylindrical core, sheet metal ends having slots therethrough, tongues at the ends of said core extending through said slots and deflected outwardly and spot welded against the outer faces of said ends, a tube 25 extending axially through said core, said

ends having central openings for receiving the tube ends, sheet metal cylindrical cap frames having tongues extending from their inner edges and spot welded against said ends, said frames having central openings 30 in line with the tube ends and having off-center openings, the peripheral sections of said ends being deflected outwardly and inwardly to form peripheral flanges, and filler material between said flanges and cap 35 frames.

4. In a spool, the combination of a cylindrical sheet metal core, sheet metal ends secured to said core and having their peripheral edges deflected outwardly and inwardly 40 to form flanges, filler material held against said ends by said flanges and having openings therethrough in axial alinement with said core, and sheet metal frames in said openings, said frames having passageways 45 therethrough in alinement with the core axis for receiving lathe centering points.

In witness whereof I hereunto subscribe my name this 12th day of April, A. D. 1918.

EBER J. HUBBARD.
